(57) **CLAIM**

The ornamental design for a battery charger as shown and described.

DESCRIPTION

FIG. 1 is a front perspective view of a battery charger showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is an enlarged view of the battery charger taken from the circle part in FIG. 3.

The broken lines in the drawings depict portions of the battery charger and form no part of the claimed design.

1 Claim, 8 Drawing Sheets
